RESISTOR

Arthur A. Schupp, Jr., La Jolla, and Harold K. Fersen, San Diego, Calif., assignors to General Dynamics Corporation, New York, N.Y., a corporation of Delaware
Filed Oct. 26, 1960, Ser. No. 65,026
2 Claims. (Cl. 338—280)

The present invention relates to resistors and more particularly to low inductance resistors having a pulsed current capacity above about 1,000 amperes.

Presently available low inductance resistors have been designed for relatively low current. When such a resistor design has been employed to construct a resistor for high currents, especially greater than 1,000 amperes, the resulting resistor has been torn apart by the magnetic forces developed in the resistor and/or has been heated to such a high temperature that the resistor has burned out.

An object of the present invention is the provision of a low inductance resistor having a pulsed current capacity of over about 1,000 amperes. Another object of the invention is the provision of a low inductance resistor which has a relatively long life with current pulses of over 1,000 amperes. Still another object is the provision of a low inductance high current resistor which is durable in use and inexpensive to manufacture.

Various other objects and advantages of the present invention will become apparent by reference to the following description and accompanying drawings.

In the drawings:

FIGURE 1 is a perspective view of a low inductance high current resistor constructed in accordance with the present invention.

FIGURE 2 is an enlarged side view of the resistor shown in FIGURE 1; and

FIGURE 3 is a cross sectional view taken generally along line 3—3 of FIGURE 2.

In accordance with the present invention a low inductance resistor is provided which has a pulsed current capacity above approximately 1,000 amperes. Generally the resistor comprises an elongated ribbon of resistive material which is bent back upon itself so as to form a pair of spaced apart, coextensively extending folded back sections. A spacer of insulating material is disposed between the folded back sections of the ribbon and an element of insulating material is disposed on the outwardly facing surface of each section. Means are provided for clamping the spacer, the folded back sections and the elements together with a pressure such that the frictional force on the sections is greater than the force due to thermal expansion of the sections.

More specifically, the resistor illustrated in the drawing includes an elongated ribbon 10 of resistance material, such as stainless steel, Nichrome, Monel, Advance metal (an alloy of 43% nickel and the balance copper), etc. The ribbon 10 is made of a cross sectional area and length which depend upon the resistance and inductance desired.

The ribbon 10 is folded over on itself through a series of alternately reverse bends extending across the width of the ribbon so as to provide an even number of spaced apart, coextensively extending parallel sections or folds 12 interconnected by portions 13. In this way, the magnetic field energy produced by the current flowing through one section 12 is substantially reduced by the magnetic field produced by the oppositely directed current in the other section 12 of the pair. Accordingly, a low inductance results. The closer the spacing between the sections 12 the lower is the inductance of the resistor. However, as the sections 12 are spaced closer together,

2

the magnetic forces tending to move the sections 12 apart become greater.

The number of folds in the ribbon 10 depends upon the desired physical size of the resistor, and the length 5 of the ribbon 10. In the illustrated embodiment, the ribbon 10 is folded seven times to form four sets of parallel sections 12.

Disposed between the folded sections 12 of the ribbon 10 are spacers 14 of hard, heat resistant insulating material, such as phenolic impregnated canvas. The spacers 14, in addition to serving as insulation between the adjacent sections 12 serve as backing members for the sections 12.

In order to increase the electrical creep path between 15 the sections 12, the spacers 14 are made wider than the ribbon 10 and are transversely staggered as shown in FIGURE 3. The spacers 14 are made longer than the sections 12 and, as shown in FIGURE 2, end spacers 16, which are short lengths of the insulating material, are disposed between the outwardly extending longitudinal ends of the spacers 16 in abutting relationship with the interconnecting portions 13, whereby the interconnecting portions 13 are retained in position.

Electrical connections are made to the ends of the ribbon 10 through a pair of spaced apart L-shaped terminal blocks 20 and 22 of conductive material, the corresponding legs of which are in parallel relationship. The terminals 20 and 22 are insulated from each other by a sheet 24 of suitable insulation, such as silicone rubber. 25 The sheet 24 is extended beyond the boundaries of the terminal 20 and between spacers 14 to increase the electrical creep path between the terminals 20 and 22. The ends of the ribbon 10 are connected to the inwardly facing marginal portions of the shorter legs 26 and 28 of the terminals 20 and 22, respectively, by suitable means, such as hard solder.

Means are provided on each of the longer legs 30 and 32 of the terminals 20 and 22, respectively, for attaching an electrical cable (not shown) thereto. In the illustrated embodiment, the attaching means for terminal 20 includes an internally threaded tubular conduit 34 suitably connected at right angles to the longer leg 30 thereof. The attaching means for terminal 22 includes an internally threaded tubular conduit 35 which is suitably connected to an offset portion 38 of the leg 32 of the terminal 22.

Elongated rectangular elements or side forms 40 and 42 of hard, heat resistant insulating material such as phenolic impregnated paper are provided on the outwardly facing surfaces of the folded ribbon 10. The ends of the elements 40 and 42 are provided with suitable recesses 44 and 46, which respectively receive the shorter legs 26 and 28 of the terminals 20 and 22. The elements 40 and 42 are respectively attached to the terminals 20 and 22 by suitable means such as screws 48 threadedly engaged with the terminals 20 and 22.

When a high current is passed through the ribbon 10, the magnetic pressure forces the ribbon 10 into any 60 voids existing adjacent the ribbon 10, that is, voids in the spacers 14 and 16, and in the side forms 40 and 42, and results in tearing of the ribbon 10. In the illustrated embodiment, such voids occur at the separations (indicated by the reference numeral 59) existing between the ends of the terminals 20 and 22 and the recesses 44 and 46. To prevent tearing of the ribbon 10, the voids 50 are filled with a hard insulating material, such as epoxy resin.

The sections 12 of the ribbon 10, the spacers 14 and 65 16 and the side forms 40 and 42 are clamped together by suitable clamping means 52 which in the illustrated embodiment, includes a plurality of transversely extend-

ing, longitudinally spaced apart clamps. Each of the clamps 52 includes a pair of steel channels 54 and 56, respectively disposed on the outwardly facing surfaces of the side forms 40 and 42. The channels 54 and 56 are connected together by bolts 58 and 60 extending through the ends of the channels 54 and 56. In the illustrated embodiment, each of the bolts 58 and 60 is provided with a nut 62 and washer 64.

When a high current is passed through the ribbon 10, the ribbon tends to lengthen due to the heat developed therein by the current. This lengthening of the ribbon 10, if not restrained, will eventually tear the ribbon apart. To prevent such lengthening the clamps 52 are spaced along the side forms 40 and 42 at such a distance and are maintained under such a pressure by the bolts 58 and 60 that the frictional force on the ribbon 10 is greater than the force due to thermal expansion of the ribbon 10.

The necessary clamping pressure may be determined by first calculating the temperature rise of the ribbon 10 assuming that all the energy supplied to the resistor is dissipated in the ribbon in a very short time. Using this temperature rise, the elongation of the ribbon may be calculated, and then using Young's modulus of elasticity for the material of the ribbon, the lengthwise pressure may be calculated. The lengthwise force is then found by multiplying the pressure by the cross-sectional area of the ribbon. The necessary clamping force is then calculated by dividing the lengthwise force in the ribbon by the coefficient of friction between the material of the ribbon and the material of the spacers 14 and 16 and of the side forms 40 and 42.

In one embodiment of a low inductance resistor, the ribbon is made of an alloy of 43% nickel and the balance copper. The ribbon is 1.125 inches wide and 0.004 inch thick and is approximately 12 feet long. The ribbon is folded 7 times and $\frac{1}{32}$ inch phenolic impregnated canvas spacers are disposed between the folds of the ribbon. The side forms are $\frac{1}{2}$ inch thick phenolic impregnated paper. The unit is clamped together by $\frac{1}{2} \times 1$ inch steel channels, which are tied together by $\frac{1}{4}$ " bolts. The channels are spaced approximately every 2 inches along the length of the resistor and the clamping force on the ribbon is equal to about 100 lbs. per bolt.

The above resistor has an inductance of less than 0.05 microhenry and a resistance of 0.6 ohm. The resistor may be pulsed over 3,000 times at one minute intervals with 20,000 ampere pulses which last for 5 microseconds without adversely affecting the structure of the resistor. The temperature inside the resistor during such an operation is about 300° F. The temperature at the surface of the resistor is about 200° F.

As can be seen from the above a resistor construction is provided which has a very low inductance and a high current capacity. The reason the resistor can withstand high currents is that the clamping pressure on the side forms is large enough so that the frictional force on the ribbon is greater than the forces due to thermal expansion of the ribbon. Another reason is that all voids into which the magnetic pressure would force and tear the ribbon are filled with hard material. Moreover, the folded sections of the ribbon extend coextensively and therefore the sidewise magnetic pressure on the ribbon is small.

Various changes and modifications may be made in the above described low inductance, high current resistor without departing from the spirit or scope of the present invention. Various features of the invention are set forth in the accompanying claims.

What is claimed is:

What is claimed is:

1. A low inductance resistor having a pulsed current capacity greater than 1000 amperes, which resistor comprises a strip of resistive material folded back upon itself

in uniform fashion to provide a plurality of coextensive parallelly arranged planar segments that are spaced apart and joined by folded end sections, a plurality of insulating spacers, one each of said insulating spacers being disposed between each pair of adjacent ones of said coextensive parallelly arranged planar segments of said strip, a plurality of insulating elements, one each of said insulating elements covering the exposed surface of each of said folded end sections of said strip, a pair of terminal blocks, a first of said terminal blocks being electrically connected to one end of said strip of resistive material and a second of said terminal blocks being electrically connected to the other end of said strip, a pair of side forms positioned along oppositely disposed planar segments of said strip of resistive material and adjacent the connection of the ends of said strip with said terminal blocks, a plurality of clamps spaced along the longitudinal axis of each of said side forms for clamping said side forms, spacers, insulating elements, and planar sections of said strip of resistive material together with a pressure such that the frictional force on said planar segments and folded end sections of said strip is greater than the force imparted thereto due to thermal expansion resulting from the passage of current therethrough, and insulating means for filling voids existing in the clamped together structure to prevent the possibility of said strip of resistive material being severed due to the action of magnetic pressure forces thereon while current is passed therethrough from said first terminal to said second terminal.

2. A low inductance resistor having a pulsed current capacity greater than 1000 amperes, which resistor comprises a strip of resistive material folded back upon itself in uniform fashion to provide a plurality of coextensive parallelly arranged planar segments that are spaced apart and joined by folded end sections, a plurality of insulating spacers, one each of said insulating spacers being disposed between each pair of adjacent ones of said coextensive parallelly arranged planar segments of said strip and extending beyond the edges thereof, a plurality of insulating elements, one each of said insulating elements covering the exposed surface of each of said folded end sections of said strip, a pair of terminal blocks, a first of said terminal blocks being electrically connected to one end of said strip of resistive material and a second of said terminal blocks being electrically connected to the other end of said strip, a pair of side forms positioned along oppositely disposed planar segments of said strip of resistive material and adjacent the connection of the ends of said strip with said terminal blocks, a plurality of clamps spaced along the longitudinal axis of each of said side forms for clamping said side forms, spacers, insulating elements, and planar sections of said strip of resistive material together with a pressure such that the frictional force on said planar segments and folded end sections of said strip is greater than the force imparted thereto due to thermal expansion resulting from the passage of current therethrough, and insulating means for filling voids existing in the clamped together structure to prevent the possibility of said strip of resistive material being severed due to the action of magnetic pressure forces thereon while current is passed therethrough from said first terminal to said second terminal.
